UNITED STATES PATENT OFFICE.

ROBERT L. MARTIN, OF THOMAS, WEST VIRGINIA.

FIRE-EXTINGUISHER.

1,108,381.

Specification of Letters Patent. Patented Aug. 25, 1914.

Application filed May 7, 1913. Serial No. 766,152.

To all whom it may concern:

Be it known that I, ROBERT L. MARTIN, a citizen of the United States, residing at Thomas, in the county of Tucker and State 5 of West Virginia, have invented certain new and useful Improvements in Fire-Extinguishers, of which the following is a specification, reference being had to the accompanying drawings.

10 This invention relates to improvements in fire extinguishers, and more particularly to that class of extinguishers which are generally designated as hand grenades.

An object of this invention is the provision of a hand grenade which is constructed of a shell of glass or other frangible material, the grenade having an expansible member disposed therein, whereby when it is broken, the member will expand and thereby scatter the extinguishing material contained within the shell.

Another object of this invention is the provision of a hand grenade which is preferably spherical in form, and which comprises a shell of glass or other frangible material, the shell being adapted to receive a normally straight helical wire spring, the spring when inserted into the shell assuming a substantially circular form by contact 30 with the wall of the grenade.

With these and other objects in view, my invention consists in certain novel constructions, combinations, and arrangements of parts, to be hereinafter more fully described, 35 claimed and illustrated in the accompanying drawing, in which—

Figure 1 is an elevation of my device partly in section; and Fig. 2 is a top plan view thereof.

40 Referring more particularly to the drawing, the numeral 1 designates a spherical shell or receptacle which is provided with a neck 2, through which a diffusible fire extinguishing compound 3 may be passed into the shell. A normally straight helical expansion spring 4 is inserted into the receptacle through the neck 2, the spring assuming a circular shape by coming into contact with the wall of the receptacle. The spring 45 50 4 is of such a length that, when operatively positioned within the receptacle, its ends

terminate to either side of the neck 2 in order that no obstruction will be afforded to the insertion within the receptacle of the fire extinguishing compound, the diameter 55 of such spring being such as to permit its ready insertion through the neck 2. A stopper 5 is disposed in the neck of the receptacle to maintain the compound and spring therein, and to prevent deterioration 60 of the compound.

In the practical use of my device, the spring 4 is first entered into the receptacle, whereupon the fire extinguishing compound is passed therein, the compound surrounding the spring and entering between the coils thereof. The stopper 5 is then disposed in the neck of the receptacle to maintain the compound therein. When the grenade is thrown against a hard object, it 70 will be seen that the shell 1 will break, and the spring 4 will assume its normal position and scatter the diffusible compound in various directions to cover a large area and thereby quickly extinguish the flame. 75

It will of course be understood that I may use either a liquid or powder chemical compound, as either is effective in use with my improved grenade.

Having thus fully described my invention 80 what I desire to claim and secure by Letters Patent is:

As a new article of manufacture, a fire extinguisher comprising a hollow shell of frangible material provided with a restricted opening, a coil spring insertible through such opening and normally in constant contact under tension throughout its entire length with the interior wall of such shell, 85 said spring being of such a length as to terminate when in applied position to either side of the opening in close proximity thereto, and a diffusible compound insertible within the shell through the opening thereof and adapted to enter between the coils of 90 95 the spring.

In testimony whereof I hereunto affix my signature in the presence of two witnesses.

ROBERT L. MARTIN.
